ROBERT GAUDARD, OF BERN, SWITZERLAND.

PANEL FRAME.

Application filed June 4, 1925, Serial No. 34,969, and in Switzerland June 6, 1924.

The object of the present invention is a panel frame, for instance for window and door panels, furniture walls, ballustrade fillings, grate-railings and the like, which by way of example may be combined to a window-frame securing all the advantages of the wooden or the iron windows or sashes, said panel frame being characterized by the fact, that at least one cover member surrounds at least one enclosure provided with a groove, said cover member and enclosure being thus arranged and combined with one another as to constitute a rigid unit adapted to receive and hold a panel.

The main advantages of this design consist in the saving of space and material owing to the fact that even with small cross sections a great rigidity may be obtained.

The attached drawing shows by way of example two embodiments of the invention.

Figure 1 is an elevation of a double window.

Figure 2 is a vertical section according to line *a-a*.

Figure 3 is a horizontal section on line *b-b*.

Figure 4 shows a corner joint by way of example.

Figure 5 is a side view according to Figure 4 and

Figure 6 is a perspective view of another embodiment of the invention.

According to the first working example (Figs. 1 to 5) the panel frame comprises an outer cover member 1, whose bottom leg is provided with a weather-rail 1^a and an inner cover member 2. These cover members 1 and 2 may be made from profiled metal bars. An enclosure 3 is fitting tightly against at least two sides on the cover and may be adapted for determining the profile height of the cross section. This enclosure 3 is provided with a groove 4 and is to be made from a material into which nails may be driven, such as wood, fibre or the like, in order to allow the glazing of the window in the usual manner by means of pins or tacks 5 and a putty packing 6.

The corner joints of the profiled bars may be made in the usual way either by riveting, soldering, welding etc., and it is evident that the cover members may be connected at convenient places between themselves in a similar manner. If one of the cover members is to surround the enclosure to such a degree

that the latter may be jammed into the cover member and thereby will be gripped tightly by the sides of the latter an intermediary connection of the cover members amongst themselves will not be necessary.

In the case that the enclosures 3 are to partake in increasing the rigidity of the individual panel frames and of the whole structure, it is advisable to interconnect the covers and the enclosures by means of pins 7 and the corner joints of the enclosures themselves as shown by way of example in Figs. 4 and 5. By interconnecting the covers and the enclosures the frame parts are constituting combined girders since the pins 7 are submitted to longitudinal thrusts, whilst the arrangement of the corner joints of the enclosures evidently reinforces frame against warping.

If the panels are of a certain size a suitable number of horizontal and vertical intermediary muntins may be arranged, which are fixed for instance by means of tenons 9 which engage in corresponding mortices 10 of the enclosure 3. By means of pins 11 the connection may be secured in a very simple manner. As a matter of course the muntins may consist of a material in which nails may be driven or may be constituted in part by such materials and a corresponding cover 85 of metal.

The panel frame shown in Figs. 1 to 5 is adapted owing to its cross section for double jointing and since its form of the frame remains virtually unchangeable owing to the metallic cover members, it will always fit tightly with unaltered exactness against the sash-frame 12, thereby warranting a perfectly tight closing of the window.

It is possible to provide for a small stuffing joint 13 for receiving a packing, say of putty, 14 which renders the connection between the panel frame and the sash frame even more tight than it is already. It is also possible to provide for a putty groove 15 by simply chamfering the edge of the enclosure and to thereby facilitate the adherence of the glazier's putty.

Fig. 6 shows a second embodiment of the invention constituting a fire-proof sash.

The panels are of wire glass and the covers 1 and 2 are connected by pins 7 traversing the enclosure 3. The muntins are made of metal. Occasional notches are provided for in the fillets for allowing to fasten the bent-

down web of the fillet against its support. The notches are to be filled in with putty after glazing.

If the panel frame is made use of for a door, the door panel may, in a similar manner as above described for the case of a window, be inserted into the groove 4 and be connected to the frame by nailing it on the enclosure or by securing it by means of a fixing fillet or the like.

In the case that the panel frame is to serve for manufacturing ballustrades or furnitures or for making walls etc., the frames proper may be replaced by single bars constituting for instance corner-posts, which impart the required rigidity to the said panels.

It is evident that the cover might be constituted by a single piece of a box-like cross section, such for example that the enclosure 3 is entirely covered, leaving only the groove 4 free, the said enclosure being thus adapted to be slid longitudinally into the cover members. It would also be possible to use cover members of U- or Z-cross section which might be slid over the top or bottom side of the enclosure.

If the panel frame is used for a double glass window a plurality of grooves 4 may be provided in the enclosures 3. The same holds good for double doors, double walls, etc. In the case of two adjacent panel frames as for instance is the case of the closed window according to Fig. 1 it may be well to provide for a covering fillet 16 with an abutment 17 which is rigidly connected with one or the other of the panel frames. In the case of corner-posts of walls the enclosure 4 may be provided with a double groove corresponding to the two panels.

The main advantages of the window according to the examples shown are:

Great increase of light and unaltered

tightness as compared with wooden window frames; and great saving in weight, possibility of nailing down the glass panels and pleasing aspect as compared with iron window frames.

What I claim is:

1. A panel frame structure, including a filler and a covering material encasing the same having angularly disposed non-engaging portions slotted at predetermined points to provide tongues bendable into engagement with the panel frame filler, and fastening elements passing through the panel frame filler and the tongues.

2. In a panel frame structure, inner filler elements and a covering encasing the same having the major portion thereof in contact with the fillers and angularly disposed out of contact with the fillers to define shoulders for engaging and holding the panel within the frame, the angularly disposed portions being slotted to provide tongues bendable into engagement with the fillers, and fastening means passing through the fillers and said tongues.

3. A panel frame structure, including a wooden filler frame and a fabricated outer sheet metal covering therefor comprising complete sections of angular cross-sectional construction having integral flanges, the inner surfaces of which are completely engaged by the filler frame.

4. A panel frame structure, including a wooden filler frame and a fabricated outer sheet metal covering therefor comprising complete sections of angular cross-sectional construction having integral flanges, the inner surfaces of which are completely engaged by the filler frame, and fastening elements extending transversely through the panel frame filler and covering.

In testimony whereof I affix my signature.
ROBERT GAUDARD.
